UNITED STATES PATENT OFFICE.

EDMUND C. MORGAN, OF NEW YORK, N. Y.; OLIVE EUGENIE MORGAN EXECUTRIX OF
SAID EDMUND C. MORGAN, DECEASED.

LONG-WALL MINING AND LOADING MACHINE.

Application filed July 2, 1921. Serial No. 432,164.

My invention relates to long-wall mining and loading machines, and one of its objects is the provision of improved and efficient apparatus of this type.

5 A further object of the invention is the provision of a mining machine having an upright series of spaced-apart dislodging tools on which powerful pressure may be concentrated, and means for feeding such 10 tools bodily along an approximately rectilinear path of travel.

Another object of the invention is the provision of an upright series of spaced-apart dislodging tools, combined with an elongated conveyor having a stationary frame 15 adapted to abut against an unmined mass along which frame such tools may be fed bodily to dislodge the material in position to be received by said conveyor.

20 A further object of the invention is the provision of an elongated sectional conveyor adapted to be anchored in position to receive material dislodged by a mining machine fed along said conveyor.

25 Other objects of the invention will appear hereinafter, the novel features and combination being set forth in the appended claims.

Referring to the accompanying drawings:

30 Figure 1 is a plan view of my improved system of mining embodying the anchored sectional conveyor, together with the mining machine, and the mechanism for adjusting the positions thereof;

35 Fig. 2 is an elevational view of the mining machine and loading mechanism along which the mining machine is fed;

Fig. 3 is a right-hand end elevation of the structure shown in Fig. 1.

40 Fig. 4 is a plan view showing details of the mining machine and the cooperative parts of the anchored section of the conveyor.

45 Fig. 5 is a sectional elevation of Fig. 4 on the line 5—5 looking in the direction of the arrows.

Fig. 6 is an elevational view of the mining machine shown in Fig. 4, showing particularly the dislodging tool mechanism.

50 Fig. 7 is a rear side view of the joint between the sections of the conveyor shown in Fig. 1, but broken away and enlarged.

Fig. 8 is a sectional view of Fig. 7 on the line 8—8 looking in the direction of the arrows.

55 Fig. 9 is a sectional elevation on the line

9—9 of Fig. 4, looking in the direction of the arrows.

Fig. 10 is an enlarged elevation of a portion of Fig. 4 on the line 10—10, looking in the direction of the arrows. 60

Fig. 11 is an enlarged sectional plan view of a portion of Fig. 5 on the line 11—11, looking in the direction of the arrows.

Fig. 12 is a sectional elevation taken on the line 12—12 of Fig. 5, looking in the direction of the arrows. 65

Inasmuch as the conveyor frame constitutes the supporting frame for the mining machine, I will first describe the conveyor mechanism. 70

Referring to Figs. 1, 4 and 9, it will be seen that the conveyor frame 13 is adapted to rest in stationary position on the floor of the mine chamber. At the rear end portions of the conveyor frame 13 are located 75 hydraulic roof jacks as shown at 14—15, Fig. 1. As shown in Fig. 9, each roof jack comprises a cylinder 16 having a shoe 17 at its lower end. This cylinder may be free to slide up and down in a cylindrical extension 18 of the conveyor frame 13; the cylinder 16 is provided with a supply pipe 19 and the usual valve mechanism for controlling the supply of liquid pressure medium to the cylinder 16 to force the plunger 20 upwardly 80 and the cylinder 16 downwardly. By having the cylinder 16 movable relatively to the conveyor frame, the latter will more readily adapt itself to the irregularities of the floor level when the roof jacks are in 85 anchored positions.

The elongated conveyor comprises a plurality of sections, as shown at 13, 21, 22, 23 and 24, in Fig. 1, each section being anchored at its rear end portions, as illustrated 95 in Fig. 9.

Furthermore, in order to permit the elongated conveyor frame to be anchored between the floor and roof, which may extend somewhat irregularly in elevation, the conveyor frame is not only made sectional, but also pivotally connected, as shown in Figs. 1, 7 and 8. In Fig. 1, pivotal connections are shown at 25, 26, 27 and 28. Fig. 7 is an enlarged rear view of a portion of Fig. 1. 100 Extending from the cylindrical guide 18 is an arm 29, which is bifurcated, as shown at the upper right-hand portion of Fig. 4, to receive the arm 30 of the next adjacent conveyor section. Fig. 7 shows the pivot 25 of 105 110

Figs. 1 and 4, and Fig. 8 shows the cylinder 31, shown at the left-hand portion of Fig. 1.

The adjacent frames 13 and 21 are pivotally connected together by a bolt 32 which passes through interlooping tubular extensions 29' and 30' from the arms 29 and 30, respectively, in the nature of the well-known door hinge. The bolt 32 has a head 33 at one end, and a nut 34 at the other end, for securely fastening the bearing hub 35 in the position shown in Fig. 8. This bearing hub is enlarged to strengthen the pivotal connection between the rear frame sections, while the pivotal mechanism between the sides of the conveyor is of smaller diameter, so as to provide sufficient space for the travel of the movable element of the conveyor mechanism.

The conveyor preferably comprises spaced-apart endless chains, with cross-flights arranged between them at intervals to slide along a stationary bed or way as shown at 36, in Figs. 4 and 5. The conveyor may be driven by a motor, as shown at 37 in Figs. 1 and 2. The rear end of the conveyor may be located at 38, as shown in Fig. 5, rearwardly of the starting position of the mining machine shown in Fig. 1.

As shown in Fig. 9, the mining machine frame 39 rests on and slides along guideways 40 and 41, which are located longitudinally of the conveyor at the sides of the slideway 36 along which the cross-flights 42 travel. The upper horizontal surface, as well as the forward vertical face of the conveyor guide-frame 41 is engaged by the mining machine frame, which is made angular in shape for this purpose, as shown in Fig. 9.

A portion of the bottom of the mining machine frame is adapted to slide over the mine floor, but in order to decrease the friction of feeding travel of the mining machine, I prefer to provide a track 43 to be engaged by a roller 44 pivotally connected to the mining machine frame, as shown in Fig. 9 in full lines, and in Fig. 4 in dotted lines. An additional guide roller is shown at 98 engaging the inside of the conveyor frame.

Each of the conveyor frame sections is provided with a rack and when the sections are pivotally connected together as shown in Fig. 1, these racks are located in alinement with each other. The rack on the frame 13 is illustrated at 45 in Figs. 4 and 5. These racks are for the purpose of being engaged by a power-operated gear 46 on the mining machine, to effect feeding of the mining machine rectilinearly along the conveyor framework while the latter is held stationary by the series of roof jacks.

The coal dislodging mechanism comprises an upright series of pointed coal-splitting tools shown at 47 and 48, in Fig. 6, with a series of intermediate trimming dislodging

members 49 connected to the tool 47, and another series 50 connected to the tool 48. In Fig. 6, I have shown the pointed piercing and wedging tools 47 and 48, each advanced forwardly beyond the auxiliary trimming tools 49 and 50. The series 49 and 50 are preferably in vertical alinement in position to trim off the mine wall between the floor and the roof.

It should be noted that the pointed claw-like fingers 47 and 48 extend in advance of the intermediate trimming dislodging tools 49 and 50 and also in advance of the floor trimming dislodging device 57. The pointed claw-like fingers 47 and 48 are positioned adjacent the roof and floor, respectively, and are pointed and wedge-shaped so as to penetrate the coal in its native bed and by wedging action due to a continuous forward movement of the pointed piercing tools 47 and 48 the coal is ripped and torn from the unmined mass so as to fall to the floor in the path of the scoop 58. The auxiliary trimming tools 49 and 50 are also in position to dislodge the native coal over an area extending between the advanced piercing tools 47 and 48. The upper claw, comprising the advanced finger 47 and the trimming tools 49, is in position to act along the roof to dislodge the coal from the face of the mine vein immediately below the roof. The lower claw, comprising the advanced piercing tool 48 and the piercing tools 50 and the piercing tools 47, are in position to plow along the floor to dislodge the coal from the working face above the floor and direct such coal immediately onto the conveyor 36. The continuous rectilinear movement of the dislodging apparatus will cause such dislodging actions to slice or strip a layer of coal from the upright working face along a path illustrated by the dotted line 100 in Fig. 1, and by reason of the floor tools 48 and 57 an approximately flat floor will be extended, and by reason of the upright series of dislodging tools 47, 49 and 50 the wall will be left approximately in an upright plane to facilitate subsequent adjustments of the entire apparatus shown in Fig. 1.

The uppermost pointed coal splitting device 47 is mounted on an arm 51, which is pivoted at 52, on a standard 53, secured to the mining machine frame 39. The rear arm 54 is pivoted at 55 to piston rod 56 of a hydraulic motor, which may be operated in a well-known manner to adjust the elevation of the pointed coal-splitting tool 47 and lock the same at adjusted elevation.

As shown in Figs. 4 and 6, the frame 39 at its forward end portion is provided with a downwardly and forwardly extending floor trimming device 57 and a scoop 58, so that the floor will be properly trimmed or leveled and the dislodged material deflected onto the conveyors which are arranged end to end.

with the single set of conveyor flights moving along the entire length of the sectional conveyor frame.

The mechanism for rotating the gear 46 so as to effect rectilinear feeding movement of the splitting tools and the movement of the dislodged material onto the conveyor bed 36 is shown in Figs. 4 and 5. A motor 59 is mounted on the rear end of the mining machine frame 39 and coupled at 60, to speed reducing gearing shown diagrammatically at 61. A bevel pinion 62 extends from the right-hand end of the speed-reducing gearing casing and meshes with a horizontal bevel gear 63, which is mounted loosely on the vertical shaft 64, the latter being in turn journaled in the bearings 65 and 66 connected rigidly to the frame of the mining machine. At the lower end of the shaft 64 is a pinion 67, which meshes with a large gear 68 on a vertical shaft 69, which is journaled in the bearings 70 and 71, connected rigidly to the mining machine frame. Secured to the vertical shaft 69 is a pinion 72, which meshes with the gear 46, as shown in Fig. 4.

By means of a handle 73 for operating a lever 74, the clutch 75 may be operated on the pivot mounted on the bracket 76, secured to the front side of the speed-reducing gear casing as shown in Fig. 4. When the clutch 75 is thrown in and the motor 59 is operating, power may be transmitted through the gearing 62, 63, 67, 68 to the pinion 72 to drive the gear 46 and thereby cause the whole mining machine to travel along the sectional conveyor. When this operation takes place the resistance due to the dislodging operation is counter-acted by the series of roof jacks and also by reason of the fact that the left hand end of the conveyor frame 13 may abut against the mine wall as indicated at 77 in Fig. 1.

In order to retract the mining machine 45 along the conveyor to the initial position shown in Fig. 4 I provide rope winding mechanism comprising a rope 77' with its free end adapted to be anchored at 78 to the rear end of the conveyor section 18. The 50 other end of the rope 77' is connected to and wound on the rope winding drum 78' mounted on a vertical shaft journaled in the cross-piece 79 rigidly connected to the mining machine frame. By means of a lever 80 pivoted to one side of the gear casing 61 a cone clutch 81 may be operated to connect or disconnect the winding drum 78' to the beveled gear 63 through the gears 82 and 83 as shown in Figs. 5 and 10.

60 After a mining operation has been effected as by moving the mining machine along the dotted line 100 of Fig. 1 the roof jacks are all released and then the motors 85 and 86 operated to operate the rope winding 65 apparatus 87 and 88 to exert pulls on the

ropes 89 and 90 to move the entire mining and loading apparatus forwardly to a new location. During this operation the frames 91 and 92 may be anchored between the floor and the roof by means of the roof jacks 70 shown diagrammatically at 93 and 94 in Fig. 1. When this adjustment of the mining apparatus is made to a new location the supplemental conveyor 95 may likewise be moved to proper position to receive the dislodged material from the conveyor 36 for delivery into a mine car 96 on a track 97 in the entry shown at the right hand portion of Fig. 1.

By referring to Fig. 1 it will be seen that the left hand end of the conveyor frame engages the mine wall and the latter therefore affords an end abutment to receive the rearward thrust of the feeding mechanism of the mining machine during the operation thereof. While the roof jacks hold the conveyor frame stationary and prevent lateral movement thereof the mine wall may be relied upon to resist the backward thrust so that sufficient force may be exerted to move the dislodging mechanism forward 90 along the path indicated by the dotted line 100 in Fig. 1. By referring to Figs. 4, 5 and 9, it will be seen that the rack 45 of the feeding mechanism is connected rigidly to the frame 36 on which the conveyor is mounted, and this frame extends rearwardly to a position where it may abut against the mine wall as indicated at 77 in Fig. 1.

Obviously those skilled in the art may make various changes in the details and arrangement of parts without departing from the spirit and scope of my invention as defined by the claims hereto appended, and I wish therefore not to be restricted to the precise construction herein disclosed.

Having thus fully described and shown an embodiment of my invention what I desire to secure by Letters Patent of the United States is:—

1. A long wall mining and loading machine comprising an elongated traveling conveyor having sectional frames arranged in tandem in alinement with each other, a series of roof jacks for individually holding the sectional frames in predetermined position, 110 a mining machine connected to and guided along said sectional frames, and means for feeding said mining machine to effect dislodgement of material from the mine wall onto said conveyor.

2. A long wall mining and loading machine, comprising an elongated traveling conveyor having sectional frames pivoted together and arranged in alinement, a series of roof jacks for individually holding the sectional frames in stationary position, a mining machine mounted on said conveyor by being guided along said sectional frames, and means for operating said mining machine, including rectilinear feed thereof 130

along said conveyor to dislodge the material from the mine wall and direct it onto said conveyor.

3. In mining and loading apparatus, the combination with a sectional supporting frame pivotally connected and arranged in alinement to constitute an elongated frame for a traveling conveyor, of an endless conveyor mounted on said frame to receive material from one side substantially throughout its length, a series of anchoring devices for said sectional supporting frame, and means for operating said conveyor while said frame remains stationary in predetermined position.

4. In conveyor apparatus, the combination with an elongated frame comprising a plurality of sections pivotally connected end to end to form an elongated conveyor bed, of spaced-apart endless chains with cross flights connected between them in position to move along said bed, and a plurality of spaced-apart roof jacks connected to the frame sections to hold the conveyor bed in stationary position during the operation of said scrapers.

5. In loading apparatus, the combination with an elongated conveyor frame adapted to rest on a mine floor, of traveling conveyor mechanism mounted on said conveyor frame, and anchoring mechanism comprising a roof jack connected to said frame to permit the latter while said jack is in anchored position to have freedom of up and down movement to adapt itself to irregularities of the floor but preventing lateral movement of said frame relative to said roof jack.

6. In loading apparatus, the combination with a conveyor having a frame adapted to rest on the floor of a mine chamber in stationary position, of anchoring mechanism comprising a roof jack and a sliding connection between the latter and said frame while said jack is in anchored position for permitting relative up and down movements of said conveyor frame while confining the latter against lateral movements, and means for operating said conveyor while being held stationary by said anchoring mechanism.

50 7. In loading apparatus, the combination with an elongated sectional conveyor frame, of pivotal connections on horizontal axes between the conveyor sections, an endless conveyor on said elongated conveyor frame, a plurality of spaced-apart roof jacks for each of said conveyor sections to hold the conveyor frame in predetermined position during the operation of said endless conveyor, and means for driving said endless conveyor.

8. In loading apparatus, the combination with a conveyor comprising a frame, of a plurality of upright tubular extensions connected to said frame, and spaced-apart roof jacks having sliding engagement with said

extensions respectively when said roof jacks are in anchored positions to hold the frame against lateral movement but to permit relative up and down movement at all times both when said jacks are anchored and when they are released.

9. In a mining and loading machine, the combination with an elongated conveyor comprising a frame adapted to be held stationary with one end abutting against the mine wall, of a series of spaced-apart anchorages for the conveyor frame between the ends thereof and at one side thereof, a mining machine adapted to travel along the other side of said conveyor in position to dislodge material from the mine vein directly onto said conveyor, and means comprising a longitudinal rack on said conveyor frame for feeding the mining machine along the conveyor, whereby the back thrust due to the mining operation is resisted by the said anchorages and the rear end of the conveyor frame abutting against the mine wall.

10. In mining and loading apparatus, the combination with a conveyor having a stationary frame, of a mining machine having mechanism for penetrating the solid face of a mine vein and by wedging action split the mineral therefrom, and mechanism comprising a rack on said frame for feeding said mining machine along said conveyor to effect a translating movement of said penetrating wedging mechanism along the face of the mine vein.

11. In a mining machine, the combination with a supporting frame adapted to have one end abut against an upright mine wall to resist backward thrusts exerted on said frame, of a mining machine movable along said frame and comprising penetrating wedging mechanism adapted to split the coal from the face of the mine vein, and power transmission gearing connected between said mining machine and said supporting frame for effecting feeding movement of the mining machine relatively to said supporting frame to operate said penetrating wedging mechanism in a direction away from the said abutting end of said frame.

12. In mining apparatus, the combination with a supporting frame, of a supplemental frame connected to said supporting frame to move relatively thereto, dislodging means mounted on said supplemental frame to move bodily therewith and comprising penetrating wedging mechanism adapted to strip coal from the face of a mine vein while partaking of the same translating movements as those of the supplemental frame when moved relatively to said supporting frame, a rack on said supporting frame, a motor on said supplemental frame, and power transmission gearing on said sup-

plemental frame connecting said motor to veyer, means for imparting a translating movement to said penetrating and digging mechanism, and adjusting mechanism comprising spaced-apart haulage apparatus connected to the end portions of said supporting frame to move the latter together with said mining machine bodily in a direction extending transversely of said conveyer for adjusting the mining and loading apparatus to a new location for another operation along the mine vein. 70

13. In mining apparatus, the combination with an elongated supporting frame, of a longitudinal rack thereon, a supplemental frame mounted on said supporting frame, longitudinal guides for confining said supplemental frame for longitudinal movement along said elongated supporting frame, 10 means comprising a motor and power transmission gearing on said supplemental frame and connected to said rack for moving said supplemental frame longitudinally along said supporting frame, and mining mechanism comprising spaced-apart penetrating wedging claw-like fingers rigidly connected to said supplemental frame to move bodily therewith to split the mineral from the face of the mine vein in large pieces. 15

14. In mining apparatus, the combination with an elongated supporting frame adapted to rest on the floor of a mine chamber and have one end thereof abutting against an upright mine wall, of a mining machine comprising means for penetrating the mine vein and by wedging action dislodge the mineral from the face thereof, and power transmission gearing connected directly between said mining machine and said supporting frame for effecting feeding movement of the mining machine in a direction away from said upright mine wall and relatively to said supporting frame to operate said penetrating wedging means while the backward thrust 35 exerted on said supporting frame is resisted by said upright mine wall. 40

15. A long wall mining machine comprising an elongated supporting frame adapted to abut against an upright wall in a mine, of a roof jack mechanism for anchoring said frame with one end thereof abutting against said upright mine wall, a mining machine comprising means for digging into and stripping coal from the face of the mine vein, 45 and power transmission gearing connected directly between said mining machine and said supporting frame for effecting feeding movement of the mining machine in a direction away from said upright mine wall and relatively to said supporting frame while the latter remains anchored by said roof jack mechanism. 55

16. In mining and loading apparatus, the combination with an elongated conveyer comprising a supporting frame, of a mining machine guided along said frame and comprising non-rotatable penetrating and digging mechanism extending in advance thereof to dislodge coal from its native bed 60 in a mine vein and direct it onto said con-

veyer, the combination with an elongated conveyer comprising a supporting frame, of spaced-apart roof jacks for said supporting frame, 80 a mining machine guided along said conveyer in position to dislodge material from a mine vein onto said conveyer, and separate and independent means connected to the end portions of said supporting frame for moving the latter together with said roof jacks and said mining machine in a direction extending transversely of said conveyer to adjust the mining and loading apparatus for another operation 85 along a mine vein. 90

17. In mining and loading apparatus, the combination with an elongated conveyer comprising a supporting frame, of a plurality of roof jacks for said supporting frame, a mining machine guided along said supporting frame, and spaced-apart separate operator-controlled self-contained haulage mechanisms connected to the end portions of said supporting frame to drag the latter together with said roof jacks and mining machine to a new location for another operation along the mine vein. 100

18. In mining and loading apparatus, the combination with an elongated conveyer comprising a supporting frame, of a plurality of roof jacks for said supporting frame, a mining machine guided along said supporting frame, and spaced-apart separate operator-controlled self-contained haulage mechanisms connected to the end portions of said supporting frame to drag the latter together with said roof jacks and mining machine to a new location for another operation along the mine vein. 105

19. In conveyer apparatus, the combination with an elongated frame comprising a plurality of sections pivoted together end to end to form an elongated conveyer bed, of an endless traveling conveyer mounted for operation along said conveyer bed, and a plurality of anchoring devices spaced along said sections to hold the same against lateral and endwise movements while permitting relative upright movements to enable said elongated frame to adapt itself to the irregularities of the surface on which it is supported. 110

20. In a mining and loading machine, the combination with an elongated traveling conveyer having sectional frames pivoted together and arranged in alinement, of a series of roof jacks for anchoring said sectional frames against lateral or endwise movements but permitting upright relative movements, a mining machine guided along said conveyer, and means for operating said mining machine including feed thereof along said conveyer to dislodge material from the mine wall and direct it onto said conveyer. 115

21. In a mining and loading machine, the combination with a conveyer comprising a frame adapted to abut against a mine wall, 120

125

of a plurality of roof jacks for anchoring said frame, a mining machine adapted to travel along one side of said frame in position to dislodge material from the mine vein 5 directly onto said conveyer, and means extending to said frame for feeding said mining machine along said conveyer while the back thrust due to the mining operation is resisted by the said mine wall abutment 10 and said main frame is held stationary by said anchoring means.

22. In mining and loading apparatus, the combination with a conveyer having a stationary frame, of a supplemental frame connected to said conveyer frame for movement relatively thereto, dislodging mechanism mounted on said supplemental frame stationarily relative thereto to move bodily therewith along lines parallel to the lines 20 of movement of said supplemental frame, and means for operating said dislodging mechanism by such movement of said supplemental frame to cause said dislodging mechanism to penetrate the coal and by 25 wedging action split such coal from the mine vein and direct it onto said conveyer.

23. In mining and loading apparatus, the combination with an elongated conveyer comprising a supporting frame, of roof jack 30 mechanism for said frame and connected thereto to move bodily therewith, a mining machine guided along said frame and comprising dislodging mechanism, and adjusting means comprising separate and independent haulage devices connected to end 35 portions of said frame to move the latter together with said mining machine bodily in a direction extending transversely of said conveyor for moving the mining and loading apparatus to a new location for another operation along the mine vein.

24. In a mining and loading machine, the combination with a supporting framework, of dislodging mechanism mounted thereon 45 and comprising a plurality of spaced-apart non-rotatable pointed wedging tools each adapted to penetrate the coal in its native bed and split the same in large pieces from the unmined mass, means for operating said 50 dislodging mechanism by moving the same rectilinearly relatively to said framework, a conveyer for transferring dislodged material toward loading position, and means movable with said dislodging mechanism to 55 direct dislodged coal onto said conveyer.

25. In a mining and loading machine, the combination with supporting framework, of conveyer mechanism mounted thereon, coal cleavage mechanism comprising a plurality 60 of spaced-apart non-rotatable pointed wedging dislodging tools arranged in an upright series and adapted to penetrate the solid face of a coal vein and tear the coal therefrom in large pieces over a wide area, means 65 for operating said coal cleavage mechanism

including rectilinear feed thereof, and means for directing dislodged coal onto said conveyer mechanism.

26. In a mining and loading machine, the combination with supporting framework, of conveyer mechanism mounted thereon, an upright series of non-rotatable pointed wedging coal splitting devices arranged in spaced relation and each adapted to penetrate the solid face of the coal vein and dislodge the coal therefrom in comparatively large lumps, means for operating said coal splitting devices by direct action on the solid face of the coal vein, and means movable along a path parallel to the movement of said coal splitting devices for engaging the dislodged coal and directing the same onto said conveyer mechanism.

27. In mining mechanism, the combination with a supporting frame, of coal cleavage mechanism comprising a plurality of spaced-apart non-rotatable pointed wedging coal splitting tools in position to dislodge the coal from the face of a mine vein extending between the floor and the roof of a mine chamber, and means for imparting a rectilinear movement to said coal cleavage mechanism along the mine wall to dislodge the coal therefrom by one continuous movement along such mine wall.

28. In a mining machine, the combination with an elongated frame adapted to rest on a mine floor, of coal mining mechanism connected to said frame to move along the latter and comprising a pointed penetrating 100 wedging tool extending diagonally forward toward the working face and away from said frame in position to split large pieces of coal from the coal vein, and means for moving the mining mechanism along said frame 105 to cause said splitting tool to operate along a path parallel to said frame but spaced therefrom laterally.

29. In mining and loading apparatus, the combination with an elongated main frame, of a conveyer extending along said main frame, a series of spaced-apart roof jacks with which said main frame has an up and down sliding engagement while said main frame abuts against the face of the mine 110 vein to resist the backward thrust exerted during the operation of the mining apparatus, a supplemental frame movable along said main frame adjacent said conveyer, non-rotatable penetrating and splitting 115 mechanism on said supplemental frame and movable therewith for dislodging the coal from the upright face of a mine vein by wedging action and directing the dislodged coal to said conveyer, and means for operating said dislodging mechanism by moving said supplemental frame and said non-rotatable penetrating and splitting mechanism along said main frame and along said conveyer while said main frame abuts 120

125

against the mine wall and is held against swerving thrusts by said spaced-apart roof jacks.

30. In a mining and loading machine, the combination with an elongated main frame, of a supplemental frame connected thereto for traveling along the same, a conveyer extending along the main frame, multiple penetrating wedging coal-splitting mechanism stationary relative to said supplemental frame to move bodily therewith along rectilinear paths in position to penetrate the solid face of a coal vein and by wedging action produce upright cleavages spaced back from the upright face of the mine vein sufficiently to dislodge the mineral in large pieces over a wide area, means for moving said supplemental frame rectilinearly along said main frame to operate said coal-splitting mechanism to dislodge the mineral in comparatively large pieces and direct such dislodged mineral to said conveyer, and means for anchoring said main frame with one end abutting against the mine wall while intermediate its ends it is held against-lateral swerving movements.

31. In a mining and loading machine, the combination with an elongated frame adapted to abut a mine wall at one end, of a series of roof jacks for anchoring said main frame to prevent the same from swerving laterally, dislodging mechanism movable along said frame and comprising a penetrating tool adapted to reach angularly forward toward the face of the mine vein to penetrate the solid material and by wedging action split the same from the mine vein over a wide area, a deflector co-operating with said tool to direct the dislodged material onto said conveyer, and means for moving the dislodging mechanism along said frame while said penetrating tool extends forward diagonally relative to the path of travel of said dislodging mechanism and outwardly from said frame to engage the working face.

32. In a mining and loading apparatus, the combination with an elongated conveyer comprising a frame having one end adapted to abut against a mine wall, of a series of spaced-apart roof jacks for holding the conveyer frame against lateral movement, a mining machine comprising spaced-apart pointed penetrating wedging tools adapted to penetrate the solid coal face and split the coal therefrom in large pieces over a wide area with a minimum production of fine particles of coal, a motor on the mining machine, power transmission mechanism operated by said motor and comprising rack gearing on the conveyer frame to effect operation of the dislodging mechanism by feeding the mining machine along said conveyer frame, and means for operating said conveyer to transfer toward loading

position the material as it is dislodged from the mine vein.

33. In mining and loading apparatus, the combination with an elongated conveyer comprising an elongated stationary supporting frame, of a supplemental frame movable along said conveyer frame rectilinearly, a plurality of pointed piercing wedging dislodging tools comprising one located at the roof of the mine chamber and another at the floor thereof and mounted on said supplemental frame to extend in advance thereof to move bodily therewith rectilinearly with a translating movement corresponding to that of said supplemental frame and adapted to penetrate the solid face of the native coal at the floor and at the roof and by wedging action rip and tear the coal over a wide area from the face of the mine vein and in large pieces, trimming dislodging tools between said pointed dislodging tools and spaced back therefrom, means for moving said supplemental frame rectilinearly along said supporting frame to effect the operation of all of said dislodging tools by concentrated pressures thereon, means for scooping up from the floor dislodged material between the working face and said conveyer, and a deflector for directing the scooped up dislodged material onto said conveyer.

34. In a mining and loading machine, the combination with an elongated supporting frame, of a traveling conveyor mounted on said supporting frame to receive dislodged coal from one side thereof and transfer such coal to the delivery end thereof, a supplemental frame guided along said supporting frame to travel along said conveyor, dislodging mechanism comprising a plurality of spaced-apart piercing wedging tools on said supplemental frame in position to penetrate the solid coal face and by wedging action split the coal from the mine vein, means for moving the supplemental frame along said supporting frame to secure operation of said dislodging tools, and means comprising a scoop for directing the dislodged coal from the floor between the working face and the conveyor onto the latter.

35. In mining and loading apparatus, the combination with a supporting frame, of a traveling conveyor thereon for receiving dislodged material at one side thereof and delivering it to one end thereof, a supplemental frame guided along said supporting frame, dislodging mechanism mounted on said supplemental frame and comprising a plurality of spaced-apart pointed penetrating wedging tools extending in advance of the supplemental frame in position to penetrate the solid coal face and dislodge the coal from the mine vein, means for effecting feed of said dislodging mechanism by movement of said supplemental frame along said

supporting frame toward the delivery end of said conveyor, and means comprising a scoop and a deflector for scooping the dislodged material from the floor between the 5 working face and said conveyor and directing the scooped coal onto said conveyor.

36. In mining and loading apparatus, the combination with an elongated supporting frame adapted to abut against an unmined 10 mass in its native bed, of non-rotatable means mounted on said supporting frame in position to penetrate the coal face in its native bed and by wedging action split such coal therefrom in large pieces over a wide 15 area and trimming off the ragged projections due to such dislodgment over the upright face of the mine vein, means for moving the dislodging mechanism along said supporting frame to effect dislodgment of 20 the coal from its native bed and such trimming of the working face while said frame abuts against said unmined mass to resist the rearward thrust due to the movement of the dislodging mechanism along said frame, 25 a traveling conveyor mounted on the supporting frame separately from said dislodging mechanism but adjacent thereto, and means for directing dislodged material from the space between the coal vein and said conveyor onto the latter.

37. In mining and loading apparatus, the combination with an elongated supporting frame adapted to have one end abut against an upright mine wall, of a traveling conveyor mounted on said frame, a mining machine guided along said supporting frame, said mining machine comprising spaced-apart penetrating dislodging tools adapted to attack the solid face and split coal therefrom by penetrating wedging action, means comprising a motor on the mining machine and a rack bar on said supporting frame with power transmission mechanism intervening for moving the mining machine along 40 said frame to operate said dislodging tools, roof jack mechanism for holding said elongated frame against lateral movement and with one end thereof abutting against said upright mine wall, said abutment against 45 the mine wall serving to resist end thrust during the operation of said dislodging tools, and rope winding mechanism adapted to be connected between said mining machine and an anchorage in the mine for retracting 50 said mining machine to restore the same to initial position while said frame is held stationary by said roof jack mechanism.

38. A long wall mining and loading machine comprising pivotally connected section- 60 al frames arranged in alignment with an elongated conveyor travelling longitudinally of such aligned sectional frames, a series of roof jacks for anchoring said sectional frames a mining machine guided along said conveyor, and means for operating said min- 65

ing machine including feed thereof along said conveyor to dislodge material from the mine wall and direct it onto said conveyor.

39. In mining and loading apparatus, the combination with a supporting frame comprising pivotally connected sections arranged in alignment, of a traveling conveyor extending longitudinally of said sectional conveyor frame in a position to receive material from one side substantially throughout 70 its length, a series of anchoring devices for anchoring said sectional supporting frame, and means for operating said conveyor while said frame is held in stationary position by said anchoring devices.

40. In conveyor apparatus, the combination with an elongated frame comprising a plurality of pivotally connected sections adapted to be arranged end-to end to form an elongated conveyor bed, of an endless 80 traveling conveyor mounted for operation along said conveyor bed, and a plurality of anchoring devices spaced along said sections to hold the latter stationary during the operation of said conveyor.

41. In loading apparatus, the combination with an elongated sectional conveyer frame with the sections pivotally connected together so as to adapt the conveyer frame to rest on a non-level mine floor, of an endless 90 conveyer mounted on said conveyer frame and adapted to travel along the sections thereof irrespective of the inclinations of said sections, a plurality of spaced-apart roof jacks for each of said conveyer sections 100 to hold the conveyer frame in a predetermined position during the operation of said endless conveyer, and means for driving said endless conveyer while said conveyer frame sections are lying on such irregular mine 105 floor.

42. In a mining machine, the combination with an elongated frame adapted to be located a short distance from the working face in a mine chamber with a space between said working face and said frame free and unobstructed, of mining mechanism comprising a penetrating non-rotatable splitting tool connected to said frame and movable along the latter in said free and unobstructed 110 space, and means for operating said splitting tool by a translating movement longitudinally of said elongated frame and along said working face to penetrate the solid coal and by wedging action split large pieces of the 115 coal from the mine vein over a wide area into said space.

43. In a mining and loading machine, the combination with an elongated conveyer spaced a short distance from the mine wall 120 working face, of coal mining mechanism comprising a pointed penetrating wedging tool adapted to split large pieces of coal from such working face, the space between said conveyer and said working face being 125 130

- free and unobstructed for movement of said coal mining mechanism, means movable with the coal mining mechanism for scooping up dislodged coal from the floor between the 5 working face and the conveyer and deflecting such scooped up coal onto said conveyer, and means for operating said mining mechanism by moving said tool longitudinally of said conveyer along said working face.
- 10 44. In a mining machine, the combination with an elongated frame adapted to abut against a mine wall and occupy a position spaced a short distance from the working face of the mine vein to afford a free and 15 unobstructed space between such working face and such frame, of mining mechanism connected to said frame to move along the latter in said free and unobstructed space, said mining mechanism comprising a penetrating 20 wedging tool for splitting large pieces of mineral from the mine vein and mounted to have a path of travel spaced laterally from said frame and parallel thereto with said free and unobstructed space intervening, and operating apparatus comprising 25 a motor on the mining mechanism and a rack gear on said frame for moving the penetrating wedging tool along said space to cause said tool to act on the solid coal in its native bed to split large pieces from the mine 30 vein while said frame abuts against said mine wall to resist the backward thrust due to the action of said operating apparatus.
45. In a mining and loading machine, the 35 combination with an elongated conveyer comprising an elongated frame and a traveling conveyer mounted thereon, of a mining
- machine spanning said conveyer transversely and extending laterally from said elongated frame, said mining machine comprising 40 spaced-apart non-rotatable claw-like penetrating wedging tools adapted to act on the coal vein in its native state and split large pieces of coal from the mine vein spaced from said frame, a deflector mounted on the 45 mining machine to move therewith along said frame, said deflector extending from the dislodging tools to a position above said conveyer, and means for moving the dislodging tools longitudinally of said frame together 50 with said deflector to operate said dislodging tools and also said deflector.
46. In a mining and loading machine, the combination with an elongated frame, of a traveling conveyer mounted thereon, a mining machine comprising a frame spanning said conveyer to a position at the rear side of said frame and extending laterally from the other side of said frame toward the working face, said mining machine comprising a 55 plurality of penetrating wedging tools movable bodily with the mining machine frame, means for scooping up the dislodged coal from the space between the working face and said conveyer frame and directing such dislodged coal onto said conveyer, and means connected between the mining machine frame and the rear side of said conveyer frame for operating said dislodging tools and said directing mechanism by translating movement longitudinally of said conveyer frame. 60
